UNITED STATES PATENT OFFICE.

ARNOLD A. WHEELOCK, OF WASHINGTON, DISTRICT OF COLUMBIA.

SHUTTER-BOWER.

SPECIFICATION forming part of Letters Patent No. 378,346, dated February 21, 1888.

Application filed May 26, 1887. Serial No. 239,436. (No model.)

To all whom it may concern:

Be it known that I, ARNOLD A. WHEELOCK, a citizen of the United States, residing at Washington, in the District of Columbia, have invented certain new and useful Improvements 5 in Shutter-Bowers, of which the following is a specification, reference being had therein to the accompanying drawing.

My invention relates to improvements in 10 shutter-bowers.

The object of my invention is to provide a cheap and reliable device for holding window-shutters at any desired angle; and it consists in the combination of devices described herein 15 and pointed out in the claim.

In the drawing I have shown my device as applied to the shutters of a window.

A indicates the shutter-bower, which may be made of a single piece of wire or of a bifurcated strip of spring-steel, or of any other suitable material; but I prefer to use a good article of steel wire, which is bent in the center to form a loop, a. The two portions of the wire are then twisted together and another loop, b, formed. Any desired number of loops may be formed in this way, the loops being designed to receive a screw-eye, B, secured to the window-sill F. The outer end of the bower terminates in two arms or parts, C and D, which are secured to hooks or rings secured to the shutters E in any suitable manner, so that they can be readily attached or detached from the shutters.

The arms C and D are elastic, and as the device is pushed out the arms spread and hold the shutters at any desired position.

Instead of a wire, I may use a bar or strap of steel having a number of openings to receive

the screw-eye or other suitable fastening device, while the outer end of the strap or bar is bifurcated or split to form the two arms C and D, which are secured to the shutters, as has already been described. Numerous modifications may be devised which would embrace the spirit of my invention.

The outer ends of the arms C and D may be secured to the inner edges of the shutters and the twisted portion moved back, so as to insert the screw-eye in the last or innermost loop, thus forming a device for holding the shutters in an open position.

It will be noticed that the device is very simple in its parts, can be readily attached to any window, and furnished at a cheap price.

I am aware that a shutter-holder has before 55 been used consisting of a single piece of wire bent to form a coil, with two ends or arms crossing each other terminating in hooks to engage rings in the window, and such construction I do not claim; but,

Having thus described my invention, what I claim, and desire to secure by Letters Patent, is—

A shutter-bower consisting of a wire or wires bent to form a shank with a series of loops or 65 eyes therein for attaching the same adjustably to a permanent point, and with an outer bifurcated or separated end to form arms for attaching to the shutters, all substantially as described, for the purpose set forth.

In testimony whereof I affix my signature in presence of two witnesses.

ARNOLD A. WHEELOCK.
